UNITED STATES PATENT OFFICE

EMIL HAUSER, OF NEW YORK, N. Y., ASSIGNOR TO MARCY FOUNDRY CO., OF PERTH AMBOY, NEW JERSEY, A CORPORATION OF NEW JERSEY

DESIGN FOR A CHAIR OR SIMILAR ARTICLE

Application filed October 25, 1930. Serial No. 37,376. Term of patent 7 years.

To all whom it may concern:

Be it known that I, EMIL HAUSER, a citizen of the United States, residing in the city of New York, borough of Manhattan, in the county and State of New York, have invented a new, original, and ornamental Design for a Chair or Similar Article, of which the following is a specification, reference being had to the accompanying drawing, forming part thereof.

The figure is a perspective view of a chair or similar article showing my new design.

I claim:

The ornamental design for a chair or similar article, as shown.

EMIL HAUSER.
